Grinding Mill.

No. 19,587.

Patented March 9, 1858.

UNITED STATES PATENT OFFICE.

GELSTON SANFORD, OF POUGHKEEPSIE, NEW YORK.

GRINDING-MILL.

Specification forming part of Letters Patent No. 19,587, dated March 9, 1858; Reissued March 1, 1859, No. 670.

To all whom it may concern:

Be it known that I, GELSTON SANFORD, of Poughkeepsie, in the county of Dutchess and State of New York, have invented a new 5 and useful Improvement in Grinding-Mills, the construction and operation of which I have described in the following specification and illustrated in the accompanying drawings with sufficient clearness to enable competent and skilful workmen in the arts to 10 which it pertains or is most nearly allied to make and use my invention.

My said invention consists in giving to the edges of a series of plates which have 15 grinding surfaces upon their adjacent sides, and which grind by means of combined lateral and longitudinal motion, a notched form which will secure the breaking or shearing of the large pieces of the feed, or 20 other substance to be ground, and its introduction between the grinding surfaces, as hereafter more fully set forth.

In the accompanying drawings Figure 1, is a side elevation of my improved mill. 25 Fig. 2, is a longitudinal sectional elevation of it. Fig. 3, is a horizontal section of it. Fig. 4, is a transverse sectional elevation.

A, A, are the side plates of the mill, which I usually make of common cast iron. 30 B, B, are the legs by which the plates A are supported.

C is the hopper.

D, D, E, E, E, are the grinding plates. The plates E are stationary except as to the 35 adjustment necessary to regulate the fineness of the meal. The plates D have both a longitudinal and vibratory motion given them by turning the crank or crank shaft

F, to which one end of these plates is attached. The other end is slotted and slides 40 upon the bolt G as shown more clearly in Fig. 2. There is an opening in the plates D around the bolt H, to allow them to slide and vibrate without being arrested by the bolt. The upper edges of the plates D and 45 E are notched as represented, to insure the breaking of the coarser particles and the introduction of their fragments between the plates, which the notched form of the upper edge of the plates, and their compound motion are when combined, admirably designed 50 to accomplish; the vertical motion of the plates D being sure to bring these coarser particles where they cannot fail to be crushed by their longitudinal action.

The fineness of the meal is regulated by the set screw I, by which the plates may be crowded closer together,—or by withdrawing it they may be allowed greater distance, 55 by which a coarser meal will be made.

The particular improvement which constitutes my said invention, and which I claim as having been originally and first invented by me is—

Giving the edges of the plates D and E 65 having a longitudinal and lateral motion with reference to each other, the notch form described or its equivalent, by which the breaking of the coarser particles, and their introduction between the plates is insured, 70 substantially as set forth.

GELSTON SANFORD.

Witnesses:

C. K. CORLISS,
PETER VANDERFORD.
